UNITED STATES PATENT OFFICE.

GLENN P. HEATH, OF AURORA, ILLINOIS.

ADJUSTABLE VENTILATOR.

Application filed April 1, 1921. Serial No. 457,767.

To all whom it may concern:

Be it known that I, GLENN P. HEATH, a citizen of the United States, residing at Aurora, in the county of Kane and State of Illinois, have invented a new and useful Improvement in Adjustable Ventilators, in which the following is a specification.

My invention relates to ventilators to be placed upon the roofs of buildings over or surrounding an opening through which the air from the room or rooms below will pass upwardly or may be withdrawn and discharged into the atmosphere.

My invention is more particularly adapted for use in the roofs or ceilings of theatres, factories, stores, and the like, and is specially designed and constructed so that it may be readily opened or closed, as desired, and the arrangement is such that it may be only partially opened during inclement weather and prevent rain, snow and other elements entering through the vent. Also the parts of my invention are so constructed and arranged that the closure may be a glass plate so as to combine with the ventilator the advantages of a sky-light. Besides having the before mentioned advantages, a particular object of my invention is to provide a more effective ventilator, capable of being adjusted so as to permit of a free and practically uninterrupted circulation and passage of air therethrough and which may also be adjusted so as to exclude the elements such as snow and rain and still be capable of performing its ventilating function, and which may also be adjusted to completely close the vent. In connection with the possibility of completely closing the vent, I have also provided an element which upon the occurrence of fire will affect the complete closure of the device so as to stop the draft and thereby to a certain extent retard or prevent the rapid spread of the flames.

I prefer to carry out my invention in substantially the manner hereinafter fully described, and as more particularly pointed out in the claims, reference being now had to the accompanying drawings that form a part of this specification.

In the drawings:

Figure 1 is a vertical central section of my improved ventilator showing the structure attached from the roof and the outlet closed.

Figure 2 is a fragmentary view of the

upper portion of Figure 1 showing the structure in fully opened position.

Figure 3 is a view similar to Figure 2 showing the structure partly closed or in "storm" position.

Figure 4 is a fragmentary transverse section on line 4—4, Figure 1.

Figure 5 is a vertical central section of my invention constructed in the manner of a sky-light and in intermediate or "storm" position.

Figure 6 is a fragmentary vertical section on line 6—6 of Figure 5 showing a side elevation of the operating mechanism illustrated in Figure 5.

Figure 7 is an enlarged sectional view of the glass retaining and mounting structure.

Referring more particularly to Figures 1 to 4 of the drawings, I have shown a suitably shaped (preferably cylindrical) body or wall 10 the lower portion of which is secured in any suitable manner in the usual opening made in the roof of the building, while the upper portion thereof extends the desired distance above the roof. To the exterior of this wall 10 is secured a plurality of brackets 11 of substantially Z-shape, the intermediate portions whereof are inclined in an upward direction and extend radially from the wall and terminate in upwardly disposed end portions that rise slightly above the top of the body.

These brackets 11 support upon their outer vertical portions a skirt or shield 12, also of cylindrical shape, that is concentric with and is spaced away from wall 10 a distance to permit a current of air between it and said body and the upper portion of the skirt or shield 12 is bent inwardly or constructed, as at 13, the purpose whereof will be hereinafter more fully explained. In practice, I prefer to have the lower edge of the skirt or shield terminate below the horizontal plane of the upper edge of wall 10 while its upper edge is disposed a distance above said wall.

Secured in spaced relation to each other upon the interior of wall 10 are upper and lower brackets 14 and 15 which consist of radially disposed arms having laterally-bent outer ends 14^a, 15^a, that are riveted or otherwise secured to the wall 10 and unite at their inner ends or points of intersection to provide hubs 16 and 17, respectively, having square or rectangular vertical guide openings. A combined supporting and ele-

vating bar 18 of angular cross-section is slidably mounted in the openings of guide hubs 16 and 17 so that it may be reciprocated in a vertical direction, and a conical 5 disk 19 is mounted upon the upper end of bar 18 by means of a socket 20 upon the underside of the disk to receive the bar.

Mounted in any suitable manner upon this disk 19 is a conical shaped hood or closure 10 element 21 the apex whereof fits over the apex of disk 19, and the lower outer edge of the hood extends across and beyond the upper end of wall 10, as seen in Figure 1 of the drawings, and in order to reinforce the 15 structure, I have provided a suitable spider having brace-arms 22 that incline upwardly to the underside of hood 21 from a central boss 23 surrounding and secured to the adjacent portion of bar 18.

20 It will be seen by referring to Figure 3, hood 21 is of a diameter slightly less than the narrowest diameter of the opening in the inwardly turned portion 13 of the skirt or shield so that the hood may be moved entirely through and above the skirt or shield whenever it is desired to entirely open the 25 ventilator, as illustrated in Figure 2 of the drawings. During inclement or stormy weather it is desirable to open the ventilator, but to prevent the elements such as rain, snow and the like, passing into or through wall 10, and to do this hood 21 is moved so that its lower edge is below the upper edge of the inturned portion 13, or about in the 30 horizontal plane of the top of the vertical part of the skirt or shield 12.

In order to raise or lower the hood 21 to its desired positions, I have provided a yoke 24 having a socketed portion 25 that is secured to the lower end of bar 18, and between the sides of the yoke is journaled a pulley 26 over the lower segment of which runs a chain, cable or the like, 27. One end of this element 27 extends upwardly from the pulley 26 to and is secured to one of the arms of bracket 14, while the remaining portion of element 27 passes upwardly in the opposite direction from pulley 26 to and through a pulley-block 28 loosely pivoted 50 on the opposite arm of bracket 14 and then downwardly a suitable distance to be in convenient reach of persons within the building to operate the ventilator. The fall of element 27 passes through a latch bracket 29 55 so that the element may be engaged thereby to retain it in any adjusted position or to lock the hood in closed position at night to prevent its being opened by unauthorized persons from the outside, who seek to invade 60 the premises. Also I have provided a fusible link 30 in element 27 so that in the event of fire the link will separate and cause the hood to close the ventilator of its own weight, thus shutting off the draft that ordinarily occurs with open ventilators.

The sky-light ventilator illustrated in Figure 5 of the drawings is substantially of the same general construction as that above described, excepting that a glass closure is provided in lieu of the conical metal hood, 70 shown in Figures 1 to 4, and in connection with this sky-light ventilator, I have shown another manner of elevating and lowering the closure structure. Mounted upon the upper end of elevating bar 18 is an upwardly 75 extending bracket 31, the arms thereof are disposed radially of the bar and the outer ends thereof are secured to a metal annulus or band 32 the inside diameter of which is slightly greater than the outside diameter 80 of wall 10 so that the former may telescope over the upper edge of the latter when the ventilator is closed.

A plate of glass 33 is carried by annulus 32 by supporting the glass on a pad of felt 85 34 to cushion the glass, the pad being disposed in a grove formed by a ring 35 of Z-section secured to annulus 32, and the glass is retained in position by means of a plurality of clips 36 that extend over the edge and both surfaces of the glass, and are secured to the annulus below ring 35. Felt strips 37 are interposed between the metal clips and the glass to cushion the latter, and in order to reinforce the whole structure, I provide tie-bars 38 extending from the arms of bracket 31 to a flanged collar 39 secured to the lower portion of elevating bar 18. 95

In order to facilitate the raising and lowering of the ventilator closure, I may employ a drum 40 around which a bight of element 27 passes, and I mount the arbor of the drum in an upright 41 extending between and secured to brackets 14 and 15, and the other end whereof is secured to 105 wall 10. A sheave 42 is mounted adjacent and secured to drum 40 over which passes an endless rope, cable, chain or the like 43, that may be used by the operator to rotate drum 40 for raising or lowering the closure 110 element. The element 27 after passing around the drum extends downwardly a suitable distance where a counter-balancing weight 44 is secured thereto and the end of element 27 is connected to a bracket 45 secured upon the interior of wall 10 of the 115 ventilator.

The operation of the sky-light structure is substantially the same as that of the preferred form with the exception that annulus 32 telescopes with the upper edge of wall 10 in closed position, although the closure element may be raised to a fully opened position above and outside the skirt or shield, or it may be moved to the position shown in Figure 5 in inclement weather to avoid admission of snow, rain or dirt. It will be obvious that still further modifications may be made without materially departing from the principles disclosed, and I desire it 120 125 130

understood that all such changes are contemplated as coming within the scope of the appended claim.

What I claim is:

- 5 A ventilator comprising a cylindrical wall, upper and lower brackets extended across the interior of said wall, alining centrally disposed guide bosses on said brackets, a vertical bar reciprocable in said bosses
  - 10 and extended above said wall, said bar positioned axially with respect to said wall and having a portion below the lower boss, a hood suitably mounted upon the upper portion of said bar and of greater diameter
  - 15 than said wall; said hood providing the sole cover for said wall and movable with said bar to and away from the upper edge of said wall to close and open the same, a cylindrical shield spaced from the upper
  - 20 portion of said wall parallel therewith and concentric thereto and extended above the same, an inwardly extended inclined flange upon the upper portion of said shield above said wall the inner or shortest diameter
  - 25 thereof being greater than the diameter of said hood, a roller upon the lower end of
- said bar below the lower boss, a second roller mounted on said structure intermediate the ends of said vertical bar, a flexible operating element extended substantially 30 from side to side of said cylindrical wall and over said second roller, said flexible element having one end pendent and the opposite end secured in opposite relation to said second roller, an intermediate portion 35 of said operating element engaged with the said first-mentioned roller, and means for releasably securing the pendent portion of said operating element whereby said hood may be adjusted to divers positions below 40 said flange to provide circuitous drafts through said structure about the edges of said flange and hood and may be elevated above the top of said flange to permit direct drafts through said structure between 45 the edges of said flange and hood.

Signed at Aurora, county of Kane, and State of Illinois, this 22 day of March, 1921.

GLENN P. HEATH.
